UNITED STATES PATENT OFFICE.

JOSEPH FITZPATRICK, OF DOUGLAS, ARIZONA.

WIRE-TAPPER.

1,290,153.

Specification of Letters Patent.

Patented Jan. 7, 1919.

Application filed March 30, 1918. Serial No. 225,735.

To all whom it may concern:

Be it known that I, JOSEPH FITZPATRICK, a citizen of the United States, residing at Douglas, in the county of Cochise and State 5 of Arizona, have invented new and useful Improvements in Wire-Tappers, of which the following is a specification.

This invention relates to a simple, cheap, easily operated and thoroughly effective 10 means for connecting a branch wire to an electric conducting feed wire, and resides in the construction, combination, and arrangement of parts set forth in the following description and falling within the scope 15 of what is claimed.

In the drawings,

Figure 1 is a perspective view illustrating the application of the improvement.

Fig. 2 is an enlarged sectional view approximately on the line 2—2 of Fig. 1.

Fig. 3 is a perspective view of the connecting member, the sections comprising the same being in their open position.

Referring now to the drawings in detail 25 the numeral 1 designates an electric conducting wire and 2 a branch wire which is tapped to the feed wire by my improvement.

The improvement contemplates the employment of a two-part casing of insulating 30 material, the sections thereof being hingedly connected as at 3. Each of the sections 4—4 is provided with a longitudinal substantially semi-cylindrical depression 5, which aline, when the sections 4—4 are brought together, 35 while the confronting faces of the sections 4—4 are provided with transverse passages 6—6 designed to communicate, approximately centrally with the passage provided by the depressions 5, when the sections 4—4 40 are brought together, it, of course, being understood that the depressions providing the transverse passage aline when the device is in its closed position.

Secured, in any desired manner in the longitudinal and transverse passages of one of the sections 4 is a conductor strip 7. This strip is substantially T-shaped and has its outer face depressed, so that the same is substantially U-shaped in cross section. In 45 both the straight and angle branches of the T-shaped conductor plate are arranged outwardly extending prongs 9. These prongs are in the nature of electric conductors, and

may be formed integrally with the conductor plate by providing the said plate with substantially V-shaped slits and bending the metal bounded by the slits outwardly, or the said prongs may comprise separable elements, connected, in any desired manner to the conductor plate. 55 60

It will be apparent that when the device is arranged upon the feed wire the prongs in the longitudinal arm of the conductor plate will pierce the outer insulation of the said feed wire and contact with the wire. 65 Likewise the prongs of the angle branch or arm of the conductor plate will pierce the insulating covering on the branch wire 2 and contact with the wire. When the sections are brought together both the feed and the 70 branch wires will be wholly received in the passages provided in the members 4—4, and when the members are in such position they are locked by a suitable spring catch which is indicated by the numeral 11. 75

In order to accommodate knots in the branch wire, the central branch or leg of the substantially T-shaped casing has the passage 6 therein provided with a deepened portion or depression 6' forming a pocket 80 for the knot. When the sections comprising the improvement are clamped or locked together and the knot, in the branch wire 2 arranged in its pocket, it will be apparent that the said branch wire cannot be accidentally removed from the device. It is believed, from the foregoing, that the simplicity and advantages of the construction 85 will be apparent without further description. 90

Having thus described the invention, what I claim is:

In a device for the purpose set forth, a casing of insulating material comprising a member which is T-shaped in plan and including two lapping sections which are hingedly connected, each of said sections having a semi-cylindrical longitudinal and a semi-cylindrical transverse passage which communicate, the transverse passage in each of the sections having a deepened portion 95 therein which aline when the sections are brought together, a substantially T-shaped conductor plate U-shaped in cross section having its longitudinal portion received in 100 the longitudinal passage of one of the mem- 105

bers and secured therein, the lateral extension of the insulator plate being comparatively short and being arranged in one of the transverse passages of the casing and terminating approximately in a line with the inner wall of the deepened portion in the said passage, both the longitudinal and

transverse portions of the conductor plate being formed with V-shaped slits and the metal bounded by the slits being bent outward to provide prongs, all as and for the purpose set forth. 10

In testimony whereof I affix my signature.
JOSEPH FITZPATRICK.
